UNITED STATES PATENT OFFICE

THOMAS P. MARTIN, OF OKLAHOMA CITY, OKLAHOMA

SHUTTER FOR RADIATORS

Application filed March 9, 1928. Serial No. 260,312.

This invention relates to shutters for radiators.

An object of the invention is the provision of a device which is simple in construction 5 that it may be readily applied to or removed from a radiator for controlling the flow of cool air through said radiator, the device being adjustable for varying the quantity of air passing through the radiator.

10 A further object of the invention is the provision of an adjustable shutter arrangement for controlling the quantity of air passing through a radiator of an automobile, the shutters being supported and adjusted by a 15 means which is adapted for the ready removal or application of the shutter to the radiator.

This invention will be best understood from a consideration of the following 20 detailed description in connection with the accompanying drawings; nevertheless, it is to be understood that the invention is not confined to the disclosure being susceptible of such changes and modifications as shall define 25 no material departure from the salient features of the invention as expressed in the appended claims.

In the drawings:—

Figure 1 is a view in elevation of the radiator of an automobile showing my invention 30 applied thereto,

Figure 2 is a vertical section taken along the line 2—2 of Fig. 1,

Figure 3 is a slightly modified form of the 35 invention shown in Fig. 1,

Figure 4 is a vertical section taken along the line 4—4 of Fig. 3,

Figure 5 is a view in elevation of a further modified form of the invention,

40 Figure 6 is a vertical section taken along the line 6—6 of Fig. 5,

Figure 7 is a view in elevation showing the invention in open position and disclosing a further modification,

45 Figure 8 is a vertical section of a further modified form,

Figure 9 is a front view of a still further modified form,

50 Figure 10 is a vertical section taken along the line 10—10 of Fig. 9,

Figure 11 is a vertical section of the device shown in Fig. 9 with the shutters in open position.

Referring more particularly to the drawings, 20 designates a radiator having a filling neck 21 and an opening 22 at the lower end thereof in which is adapted to be inserted the usual crank for turning over the engine.

A plurality of shutters 23, 24 and 25 have their adjacent edges overlapping and are 60 maintained in position by means of a cord having two sections 26 and 27. The sections of the cord are connected to an elastic member 28 such as a spring and said elastic member is engaged around the filling neck 21. An 65 elastic member 29 has one end engaging a perforation 30 in the lower shutter 25, and the other end engaged within the opening 22.

It will be noted that each section of the cord is passed through similar openings in the 70 shutters and since these cords pass through openings which are at right angles to the general direction of the cord, the edges of the openings will exercise a frictional grip on the cord for aiding in maintaining the 75 shutters in a predetermined position. The section 26 which extends from the elastic member 28 passes through an opening 31 from the under face of the shutter 23 outwardly and over the outer face of said shutter 80 and after being received by a notch 32 in the lower edge of the shutter 23, the cord is trained over the rear portion of the shutter 24 and brought forwardly through an opening 33 in the upper end of the shutter 24 85 whence it is carried downwardly and passed readily through a notch 34 in the lower end of the shutter 24 and then disposed over the upper end of the shutter 25 and inserted through an opening 35 in the shutter 25, whence 90 the cord is carried across the rear face of said shutter as shown in dotted lines at 36 in Figure 1 and is then brought forwardly through a perforation 37, carried upwardly through the notch 38 and inserted 95 through a perforation 39. This portion of the cord which is indicated by the numeral 27 is carried rearwardly of the shutter and brought forwardly through a notch 40 and brought upwardly over the outer face of the shutter 100

23 and then trained along the rear face of said shutter after the cord has been passed through an opening 41. The free end of the portion 27 of the cord is connected to the resilient member 28. Perforations 42 disposed in the adjacent edges of the various shutters provide means for the reception of a securing means when desired for aiding in maintaining the shutters in position.

10 The shutters shown in Figs. 1 and 2 are in substantially closed position and it is only necessary to release the elastic member 28 from the filling neck or nipple 21 and move the upper shutters downwardly to the position desired. In the open position the upper shutter 28 is located outward of shutter 24 which is in contact with shutter 25 and outwardly thereof. It will be noted in this case that portions of the cord will be positioned between the shutters so that it is necessary to provide additional means to permit this overlapping of the cord at the rear of the two upper shutters and I have provided an extension 66 of the elastic member 28 which has a hook 67 to provide for the additional length of cord required for the purpose. However, when the shutters are closed the elastic extension 66 is not employed.

15 The slightly modified form of the invention shown in Figs. 3 and 4 and in which the sections 50 and 51 of the cord are passed through perforations 52 of the shutter 53, with the free end of the sections of the cord being connected to an elastic member 54 engaging with a filling nipple 55 of the radiator 56. The sections of the cord after being inserted through the perforations 52 are brought over the outer face of the shutter and are passed through notches 57 of the shutter 58 and then brought upwardly and around the outer face of the shutter 59 and then downwardly, over the rear face and inserted through perforations 58 of a shutter 59. The sections are carried over the outer face of the shutter and then through notches 60 of the shutter 59, and thence through perforations 61 formed in the upper end of the shutter 62. An elastic member 63 has its ends engaged in perforations 64 in the shutter 62 and is trained around a crank 65. The shutters 53, 59 and 62 are adjustable relative to each other and these shutters may be moved to the lowermost position for permitting a greater quantity of air to pass through the radiator when desired. In view of the fact that the greater portion of the cord will be required for the opening of the shutters I have provided an extension 66 of the elastic member 54 connected at 68 to one end of the section 50 of the cord and has a hook 67 adapted to engage over the section 51 to provide for the overlapping of the cord when the shutters are closed, and when the shutters are applied to radiators of different heights. The extension 66 and hook 67 are similarly applied to

70 the construction shown in Fig. 1. When the hook 67 is released from its position in Fig. 3, the upper end of the cord is secured to the hook 67 thereby lengthening the elastic member 54 and providing for slack in the cords 50 and 51, which slack is utilized as noted above.

75 Referring to Figs. 5 and 6, it will be seen that when the modified form of the invention is applied to a radiator 70 in which the shutter 71 is provided with pairs of perforations 72 and 73 to receive the sections 74 of the cord, which has its free ends connected to an elastic member 75 engaging around a filling nipple 76. The cord is brought downwardly over the outer face of the shutter 71 over the upper edge of a shutter 77, through perforations 78 and then downwardly at the rear face of the shutter 77 and outwardly through perforations 79. The lower end of the shutter 77 is provided with an elastic member 80 which is adapted to engage around a crank 81 for maintaining the shutter in position.

80 The shutter 71 is adapted to be moved downwardly and be located at the rear of the shutter 77 when it is desired to supply more air to the radiator as illustrated in another form shown in Fig. 11. The threading of the sections 74 of the cord through the restricted perforations in the shutters will aid 85 in maintaining the shutters in any position desired.

85 A further modified form of the invention is shown in Figs. 7 and 8 and in which the threading of the sections 74 of the cord is varied so that when the shutter 82 is moved downwardly, as shown in Fig. 8, a portion 83 of the cord will be received within the shutter 82 with the portion 84 of the cord being located between the shutter 82 and the shutter 85. The lower end of shutter 85 is connected by means of a hook 86 to an opening 87 through which the crank is inserted for turning over the engine. The shutter 82 is provided with perforations 88 through which the cord is inserted and shutter 85 is provided with perforations 89 and 89^a to receive the cord.

90 A still further modified form of the invention is shown in Figs. 9 and 10 and in which a variation in the threading of the cord is disclosed. Shutter 90 is supported on the outer face of the radiator 91 by means of a cord 92 engaged at its upper ends to an elastic member 93 engaging a filling nipple 94. The cord is inserted through perforations 95, the shutter 90 and then downwardly and passed through perforations 96 in shutter 97. The lower end of the shutter is provided with perforations 98 which receive hooks 99 for connecting the lower shutter to a fixed part 100 of the automobile. In this form as in the form shown in Figs. 6 to 8, inclusive, the upper shutter 92 is adapted to be moved to the 105

rear of the shutter 97 when it is desired to have more air pass through the radiator.

When desired a cord 103 is trained around the rear face of the radiator and has its ends connected to perforations 102 in the shutter 77 by means of elastic members 101, Fig. 5. Such a cord and elastic member may be employed with each shutter in all the forms.

I claim:—

- 10 1. A shutter arrangement for radiators of automobiles comprising a plurality of shutters having perforations, a cord threaded through the perforations and permitting adjustment of the shutter, elastic means for connecting the shutter to a radiator, and certain of the shutters having notches to provide for a variable adjustment of the shutters relative to each other, and for releasing the lower end of the shutters from the cord.
- 20 2. A shutter arrangement for radiators of automobiles comprising a plurality of shutters provided with perforations and slidably mounted, cords threaded through the perforations to permit sliding of the shutters in predetermined position, resilient means for supporting the shutters on the radiator, the edges of the perforation frictionally engaging the cords for aiding in retaining the shutters in position when adjusted, the lower edges of the shutters having notches to receive the cords for aiding in retaining the shutters in position and permitting ready overlapping of the lower ends of the shutters on the upper end of an adjacent shutter.
- 30 3. A shutter arrangement for radiators of automobiles comprising a plurality of shutters provided with perforations and slidably mounted, cords threaded through the perforations to permit sliding of the shutters in predetermined position, resilient means for supporting the shutters on the radiator, certain of the shutters having notches in the lower edges thereof to receive the cords for aiding in retaining the shutters in a predetermined position and to permit freedom of adjustment of said shutters.

THOMAS P. MARTIN.
